UNITED STATES PATENT OFFICE.

EDGAR W. HOOVER AND JOHN A. COLEMAN, OF DANVILLE, KENTUCKY.

RAILROAD TRACK-MOTOR.

1,075,420.

Specification of Letters Patent.

Patented Oct. 14, 1913.

Application filed October 24, 1912. Serial No. 727,529.

To all whom it may concern:

Be it known that we, EDGAR W. HOOVER and JOHN A. COLEMAN, citizens of the United States, residing at Danville, in the 5 county of Boyle and State of Kentucky, have invented a new and useful Improvement in Railroad Track-Motors, of which the following is a specification.

This invention relates to a track motor 10 designed to be operated by the passage of a train of cars.

It is well known that an enormous pressure is exerted upon a track by the weight of the engines and cars passing over the 15 track. This pressure so far as we are aware has never been utilized for any practical purpose other than the operation of signal devices and the setting of switches.

The object of our invention is to employ 20 such pressure for the purpose of actually actuating a pump or other machinery, thereby effecting a considerable saving in power and performing automatically work which is now done by pumping engines in 25 charge of an engineer.

It is a common practice upon some railroads to locate water tanks adjacent a small stream and to employ a pump and engine for the purpose of keeping said tanks filled.

30 By means of our invention the passage of trains along the road can be made to automatically operate such a pump, thereby automatically pumping a certain amount of water into the tank each time the train 35 passes the same and the power obtained from the invention of course can also be applied to the performance of other work than that of pumping water if desired but the use of the invention in connection with 40 water tanks will illustrate one of its advantages.

The invention consists of the novel features of construction hereinafter described, pointed out in the claim and shown in the 45 drawings in which,

Figure 1 is a side elevation, parts being in section, the various parts being shown in normal position. Fig. 2 is a similar view parts being shown in the position occupied 50 when a track plate is depressed by the flange of a wheel. Fig. 3 is a top plan view. Fig. 4 is a section on the line 4—4 of Fig. 3. Fig. 5 is a section on the line 5—5 of Fig. 2. Fig. 6 is a section on the line 6—6 of Fig. 1.

55 In these drawings, 1 represents the track rails supported upon the usual ties 2. A

suitable plate 3 is supported by two of the ties and carries depending lugs 4, which extend downwardly between the ties and between said lugs is pivoted a rocking lever 5, 60 the inner end of which extends beneath the rail. Loosely connected to said inner end is an upright bar 6, which carries at its upper end a plate 7 adapted to be engaged by the flanges of the car wheels. This bar 65 is held in normal position by a suitable spring 8 which bears upon its lower end. In a suitable bearing 9 is pivoted a bell crank 10, the short arm of which is pivotally connected to the lever 5 by means of 70 a link 11. In suitable bearings 12, one of which is shown, is slidably mounted a rod 13 provided with a cushion spring 14 adapted to be engaged by a nut 15 which forms a head for the rod. Upwardly extending lugs 16 are carried by the rod and between said lugs is pivoted one end of a rod 17, the other end of which is pivotally connected to the long arm of the bell crank. A pawl 17 is also pivoted to the rod 13, being held in normal position by springs 18. 75 A ratchet 19 is fixed upon a suitable shaft 20, which also carries a fly wheel 21, and power may be taken from said shaft by means of a pulley 22, or by means of any 80 other mechanical equivalent.

Normally the parts will remain in the position shown in Fig. 1 but upon the passage of a train each wheel traveling upon the rail adjacent to the plate 7 will engage 90 said plate and will force the same into the position shown in Fig. 2, thereby through the levers and links above described reciprocating the rod 13 and bringing the pawl into engagement with the ratchet thereby imparting a certain rotation to the shaft 20. 95 As each car would have from four to six wheels adapted to engage said plate 7 and as a large number of cars might constitute one train it will be readily understood that 100 the rod 13 will be reciprocated a large number of times during the passage of a single train. Furthermore if the device is used in connection with a water tank many trains would pass said tank without stopping, so 105 that there would be during each twenty four hours a considerable accumulation of water in the tank.

The device is of course especially adapted for roads having a heavy traffic and running 110 a very large number of trains. The invention can also be employed for the purpose

of compressing air, the compressed air to be employed for any purpose desired, such as the operation of switches or signals.

What we claim is:—

- 5 A device of the kind described comprising a power shaft, a ratchet arranged thereupon, a reciprocating rod, a pawl pivotally carried by said rod and adapted to operatively engage said ratchet upon movement
10 of the rod in one direction, a spring adapted

to move the rod in the other direction, and means operated by the passage of car wheels for moving the rod in the direction in which the pawl operatively engages the ratchet wheel.

EDGAR W. HOOVER.
JOHN A. COLEMAN.
